UNITED STATES PATENT OFFICE.

WILLIAM C. EDGE, OF NEWARK, NEW JERSEY.

INLAID WORK AND PROCESS OF MAKING THE SAME.

SPECIFICATION forming part of Letters Patent No. 268,469, dated December 5, 1882.

Application filed September 28, 1882. (No model.)

To all whom it may concern:

Be it known that I, WILLIAM C. EDGE, of Newark, in the county of Essex and State of New Jersey, have invented a new and useful Improvement in Inlaid Work and Process of Producing the Same, of which the following is a specification.

Figure 1 represents a face view of the stamped metal from which my improved inlaid work is made. Fig. 2 is a cross-section of the same. Fig. 3 is a plan view thereof after the projections have been cut away to show the lower metal. Fig. 4 is a cross-section thereof, and Fig. 5 is a cross-section showing the inlaid work made from three thicknesses of metal.

Heretofore inlaid work, showing two or more kinds of metal in a metallic ground, was produced by cutting into the metallic ground, and then filling the spaces thus obtained with the metals of different color, so as to produce the requisite design. Damascene-work, where steel is inlaid with gold or brass, and other costly and beautiful specimens of inlaid work, were thus made and were highly prized, because of their great beauty and durability; but the cost of production was necessarily very great, and it required the most skillful attention to produce a perfect specimen of such inlaid work.

My invention consists in producing the same effect as Damascene-work, or any other suitable effect that may be desired, by superposing the metals of which the work is to be composed in slices one upon the other, then embossing them so as to raise the lower slice of metal where it is embossed into the plane of the upper slice, and then filing or cutting away such portions of the embossed projections as are desired to produce the design. Thus, for example, where only two colors are desired to be shown—namely, one on the background of the other—two slices, *a b*, of metal are used, as in Figs. 1, 2, 3, and 4. These two slices are so placed that the one, *a*, for the ground-work shall be on top and the other, *b*, for the ornamental scrolls, &c., at the bottom. The two slices *a b* are united by what is known as "plating," or in any other proper way to permanently remain in connection with one another, and they are then placed into an embossing-

machine, which will strike up such ornaments as it may be desired to have struck up for the production of the requisite design. (See Figs. 1 and 2.)

The embossing-machine is to operate in such a way that the projecting parts of the lower plate, *b*, will extend into the plane of the upper plate, *a*, as is clearly shown in Fig. 2. The metal having been brought into the condition shown in Fig. 2, the embossed projections are next filed off, more or less, so that the covering of the plate *a*, above the stamped-up portions of the plate *b*, is removed, thus leaving a trace or scroll of suitable outline of the lower metal visible in the background of the upper.

It will be seen that the production of inlaid work on this plan is not expensive beyond the mere cost of the metal itself, and that the most beautiful effects can thus be produced. The more slices of metal are used the richer of course will be the effect. Thus in Fig. 5 are shown three slices, *a b c*, united together—say the upper slice, *a*, of steel, the next lower slice, *b*, of gold, and the lowermost slice, *c*, of silver or white gold. When these slices have been properly plated or united, they are stamped up in the embossing-machine, so that the metal of the lowermost plate, *c*, is carried into the plane of the uppermost slice, *a*, at such parts where it is desired to show the color of the lowermost plate. At other parts where that color is not to be brought out, the raise produced by the embossing-machine must suffice to bring the metal of the slice *b* into the plane of the slice *a*. After the embossing-machine has done its work, the filing-off commences and produces on the surface of the steel, which thus becomes perforated, outlines of gold or outlines of gold bordered with silver, or, if desired, outlines of silver only. The embossed parts may be filed off entirely, if desired, so as to leave the upper surface of the plate *a* quite smooth when the work is finished; or suitable parts of the embossing may be allowed to remain raised, so as to heighten the effect. The lower slice may be made of sections of different metals, placed side by side, to increase the effect.

I do not limit myself to any kind of metal from which this work can be made, nor to any mode of joining the two or more slices, nor to

any kind of embossing-machine in which the slices are embossed, nor to any method of cutting off the embossed projections so as to show the lower metal in the upper, as this 5 may be done either by filing, shearing, etching, or otherwise.

I claim—

1. The method herein described of producing inlaid work, which consists in intimately 10 connecting two or more slices of metal, in then embossing them so as to bring parts of the lowermost slice into the plane of the uppermost slice, and in then cutting down the em-

bossed parts to show the metal of the lower slice or slices in that of the upper, substantially as described. 15

2. Inlaid work composed of an upper perforated slice, *a*, of metal, and of one or more lower slices, each of which extends beneath the slice *a*, and projects also into the perforations of said slice *a*, substantially as described. 20
